UNITED STATES PATENT OFFICE.

ISIDOR M. COLE AND BURR MCKINNEY, OF INDIANAPOLIS, INDIANA.

SIGNALING DEVICE.

1,378,584.

Specification of Letters Patent. Patented May 17, 1921.

Application filed June 18, 1920. Serial No. 389,839.

To all whom it may concern:

Be it known that we, ISIDOR M. COLE and BURR MCKINNEY, citizens of the United States, and residents of Indianapolis, in the 5 county of Marion and State of Indiana, have invented certain new and useful Improvements in Signaling Devices, of which the following is a specification.

Our invention relates to clock controlled 10 signaling devices and has for its purpose to provide an improved device of this character adapted for use in manufacturing plants, schools or under any conditions where it is desired to signal the beginning and termina- 15 tion of the periods of a time set program.

It is also our purpose to provide an improved device of this character into which a standard type of clock can be incorporated as one of its elements with a minimum 20 amount of additional equipment, which will be highly efficient in use, and in which the parts can be manufactured and installed at a relatively small cost.

We will describe our invention in the best 25 form known to us at present and as associated with a steam whistle signal, but it will be apparent that the same is susceptible to association with various types of signals for their efficient and correct operation and 30 that the arrangement, construction and forms of the various parts are capable of being changed with the exercise of only ordinary mechanical skill and without departing from the scope of the invention as set 35 forth in the appended claims.

In describing my invention in detail reference will be had to the accompanying drawings wherein like characters of reference denote corresponding parts in the several views, and in which—

Figure 1, is a diagrammatic view of our improved clock control signaling device, the signal operating mechanism being disclosed in end view;

Fig. 2, a plan view of the signal operating mechanism partly in section;

Fig. 3, a side view of the signal operating mechanism;

Fig. 4, a section on the line 4—4 of Fig. 2;

Fig. 5, a fragmental side view of the clock element of the device;

Fig. 6, a front view of what is shown in Fig. 5;

Fig. 7, a section on the line 7—7 of Fig. 6; and

Fig. 8, a section on the line 8—8 of Fig. 6.

Referring to the drawings A indicates generally the controlling clock of our device which may be of any standard make and operated either mechanically or electrically 60 and which includes the usual dial face 10, hour hand 11, minute hand 12, and an hour hand arbor 13 all of well known arrangement and construction.

In carrying our invention into practice 65 we fix on the hour hand arbor a disk 14 of insulating material located preferably directly behind the dial face 10 as shown in Fig. 5. This disk 14 has embedded in its front face a distributor ring 15 which is 70 electrically connected with contacts 16 projecting from the periphery of the disk and socketed radially in the latter. The body of each contact 16 carries a medial metallic strip 17 which is electrically connected to 75 the ring 15 by a screw 18 as will be obvious. During the rotation of the disk 14 in unison with the hour hand 11 these contacts are adapted to successively enter into momentary engagement with a circuit terminal 19 80 mounted on the frame of the clock and having a flexing contact point 20, which is tensioned by the engaging contact so as to render certain and positive an effective momentary electrical connection between the 85 terminal 19 and contact 16. To allow quick disengagement of the flexed point 20 from the strip 17, as shown in Fig. 5, and thereby prevent arcing we cut each contact away sharply as at 21 so that the point 20 can 90 move quickly to normal position immediately it becomes disengaged from the strip 17 by movement of the disk 14. It will be apparent that the number of contacts 16 may be varied according to the number of per-

iodical operations at the signal desired and it will also be apparent that these contacts 16 are placed around the periphery of the disk 14 so as to bear a definite relation to the hour hand 11, such relation being de- 100 termined by the hours of the day at which it is desired to produce signals. Also mounted on the frame of the clock is another circuit terminal 21' which includes a spring projected contact 22 always in engagement 105 with the distributor ring 15. From the foregoing it will be apparent that any electric circuit having the terminals 19 and 21' will be normally open and closed through the distributor ring 15 when the contact point 20 110

engages the metal strip 17 as the result of rotation of the disk 14 in unison with the hour hand 11.

Our invention further embodies a signal operating mechanism adapted to be actuated initially by the closing of an electric circuit effected by connecting the terminals 19 and 21' by the contact finger 20, contact 16, ring 15 and contact 22 in the manner heretofore described; the continued actuation of such mechanism for one cycle being accomplished by closing another circuit in a manner to be presently referred to. This signal operating mechanism can be disposed in any desired location, preferably near the signal to be operated, and is shown as comprising an electric motor 23 having a motor shaft 24 which is disposed in axial alinement with a shaft 25 rotatably and slidably mounted on a bearing bracket 26. The shafts 24 and 25 are clutched together by means of a disk 27 of relatively soft metal such as brass or bronze fixed on the shaft 25 and a disk 28 of relatively hard metal, such as steel fixed on the shaft 24. The bearing pressure of the disk 27 against the disk 28 is determined by the compression of a spring 29 housed in an extension 30 of one of the bearings of the bracket 26, which extension 30 is closed by a cap 31 in which a compression screw 32 is threaded and through the instrumentality of which latter the compression of the spring 29 may be adjusted and thereby the pressure of the disk 27 against the disk 28. The clutching action afforded by the engagement of the relatively hard metal of the disk 28 with the relatively soft metal of the disk 27 is such that the parts of the mechanism operated by the rotation of the shafts 25 will not be subject to sudden shock and too quick starting. Disposed adjacent the bracket 26 is another bearing bracket 33 in which is rotatably mounted a shaft 34 having its axis of rotation parallel to the axis of rotation of the shaft 24 and 25. Fixed on one end of the shaft 34 is a gear wheel 35 which meshes with a pinion 36 fixed on the shaft 25. One of the spokes of the wheel 35 is provided with a radially disposed slot 37 in which is slidably adjustable a member 38. Secured to this member 38 is one end of a connection 39 and the other end of this connection is shown secured to the valve operating arm 40 of a signal whistle 41. By this construction it will be apparent that when the motor 23 is operated the gear wheel 35 will be rotated and the consequent movement of the member 38 acting through the connection 39 will in turn operate the valve arm 40 to blow the whistle 41. It will of course be understood that the valve controlled by the arm 40 is of the spring type and is maintained normally closed so that when one complete revolution of the gear wheel 35 is made said

valve will automatically close. In other words the operation of the whistle 41 will be effected for a predetermined period by each rotation of the gear wheel 35. The amount of movement transmitted to the arm 40 can be controlled by adjusting the member 38 in the slot 37 as will be obvious. While we have shown in this instance, for the purpose of illustration, a signal in the form of a steam whistle to be operated by the rotation of the wheel 35 it will be apparent that the type of signal can be varied as desired and that the connections between the signal and the wheel 35 can be arranged in various ways to suit the particular conditions to be met.

We will now describe the various electrical connections between the terminals 19 and 21' and the motor 23. Fixed on the end of the shaft 34 remote from the wheel 35 is a disk 42 of insulating material which has embedded in its outer face a split distributor ring 43 forming between its ends a cut-out 44. It will be observed that by mounting the disk 42 on the shaft 34 said disk will make one revolution for every revolution made by the gear wheel 35. This disk 42 is provided with a metallic hub portion 45 which is connected with the ring 43 by a conductor 46. Mounted adjacent the outer face of the disk 42 is a bracket 47 which carries a contact 48 disposed at its upper end and in position to engage the ring 43 during rotation of the disk 42. The bracket 47 is provided with a lateral arm 49 the free end of which carries a contact 50 also adapted to engage the ring 43 as the disk 42 rotates and likewise engage the cut-out portion 44 of the disk at one period in the rotation of the latter. This cut-out 44 is engaged by the contact 50 when the disk is at rest or in its normal position. Another contact 47' is carried by the bracket 47 and constantly engages the metallic hub portion 45 of the disk 42. The feed lines of our signaling device are indicated at 51 and 52 and are connected respectively with switch terminals 53 and 54 of a switch 55. This switch also includes terminals 56 and 57, the former being connected to the terminal 21' by a conductor 58 and to the contact 50 by a conductor 59. The switch point 57 is connected to one pole of the motor 23 by a conductor 60, while the other pole of said motor is connected to the contact 47' by the conductor 65. The terminal 19 is connected to the contact 48 by a conductor 61 which at one point forms a coil for a magnet 62 adapted when energized to operate a pivoted armature in the form of a gravity latch 63 which latter cooperates with a stop 64 on the disk 42 to prevent rotation of the disk 42 at the termination of each cycle of operation of the signal operating mechanism that would tend to move

said disk to a position that would bring the contact 50 into engagement with the distributor ring 43.

Assuming that the switch 55 is closed 5 with respect to the feed line conductors 51 and 52 it will be apparent that when one of the contacts 16 is engaged with the contact finger 20 by rotation of the disk 14 a circuit will be closed through the conductor 10 58, terminal 21', contact 22, distributor ring 15, contact 16, terminal 19, conductor 61, contact 48, distributor ring 43, conductor 46, metal hub portion 45, contact 47', conductor 65, motor 23 and conductor 60 which 15 circuit is directly controlled by the clock mechanism heretofore described and is termed a "secondary circuit." As soon as this circuit is closed the magnet 62 is energized and attracts the latch 63 to unlocked 20 position with respect to the stop 64 so that the disk 42 is then free to rotate as a result of the operation of the motor 23. At the same time the closing of this secondary circuit in the manner referred to operates the 25 motor 23 to actuate the signaling device 41 in the manner heretofore described. It will now be observed that the engagement between the terminal 19 and the contact 16 is only momentary due to the constant movement 30 of the disk 14 and provision must be made for maintaining the motor 23 in circuit if any appreciable operation of the signal 41 is to be had. This is accomplished by reason of the fact that as soon as the 35 motor 23 begins to rotate a like condition is established with respect to the disk 42 and while the secondary circuit is still closed sufficient rotation is imparted to the disk 42 to bring the contact 50 into engagement 40 with the distributor ring 43. When this condition arises a circuit is closed through the conductor 59, contact 50, distributor ring 43, conductor 46, metal hub portion 45, contact 47', conductor 65, motor 23 and conductor 60. This circuit we term the "primary circuit" and its closure is maintained 45 by the connections just described until the disk 42 and wheel 35 have made one complete revolution which will again cause engagement 50 between the contact 50 and the cut-out 44 to automatically open the primary circuit. In the meantime the secondary circuit having been broken by the movement of the disk 14 the magnet 62 has been 55 come deenergized and the latch 63 is moved by gravity to a position to be engaged by the stop 64 and thus positively stop rotation of the disk 42 while the contact 50 is in engagement with the cut-out 44. Thus it 60 will be obvious that the normally open status is restored to both the secondary and primary circuits after the signal actuating

mechanism has completed one cycle of operation. When another contact 16 on the disk 14 engages the contact finger 20 the operation just described will be repeated. 65

We claim—

1. In an electric program clock, a disk of insulating materials fixed on the arbor of the hour hand of the clock, a distributor 70 ring seated in the disk with its outer periphery in spaced relation to the periphery of said disk, a plurality of radial contacts carried by the disk and electrically connected with the distributor ring, said radial contacts projecting beyond the periphery of the disk, a bracket mounted on the clock and extending across a portion of the face of both the disk and distributor ring, a spring projected contact carried by the bracket and 75 constantly engaging said distributor ring, a second bracket mounted on the clock, and a contact carried by the second bracket for successively engaging the radial contacts during rotation of the disk. 80

2. In a clock controlled signaling device, the combination of a signal, an electric motor, a normally open circuit for the motor, a rotatable shaft operatively connected with the motor, a pinion on said shaft, a gear wheel meshing with the pinion, a member carried by and adjustable radially of the gear wheel, a connection between said member and signal whereby the rotation of the gear wheel will operate the signal, clock 90 controlled means for closing the motor circuit, and means operated by the motor for breaking the motor circuit when the gear wheel has completed one revolution. 95

3. In a clock controlled signaling device, 100 the combination of a signal, an electric motor and its shaft, a normally open circuit for the motor, a rotatable shaft aligned and frictionally connected with the motor shaft, said rotatable shaft being mounted 105 for longitudinal movement in its bearing, adjustable spring means acting longitudinally on the rotatable shaft to intensify and diminish the frictional connection between said shafts, connections between the rotatable shaft and said signal whereby the rotation of said shaft will operate the signal, clock controlled means for closing the motor circuit, and means operated by the motor for breaking the motor circuit at a predetermined time. 110 115

In testimony whereof we hereunto affix our signatures in the presence of two witnesses.
